DESIGN FOR A CABINET

Jerome E. Moberg, Ellicottville, N. Y., assignor to
Alfred E. Taylor, Detroit, Mich.

Application July 13, 1946, Serial No. 131,552

Term of patent 14 years

(Cl. D33—19)

To all whom it may concern:

Be it known that I, Jerome E. Moberg, a citizen of the United States, residing in Ellicottville, in the county of Cattaraugus and State of New York, have invented a new, original, and ornamental Design for Cabinet, of which the following is a specification, reference being had to the accompanying drawing, forming a part thereof, wherein:

Figure 1 is a perspective view of the cabinet showing the front, side, and top;

Figure 2 is a perspective view of the cabinet showing the other side and top; and

Figure 3 is a view taken substantially along the line 3—3 of Figure 1.

The dominant features of the invention are shown in full lines. The dot and dash showing of the rear portion of my cabinet is to indicate an indeterminate length.

I claim:

The ornamental design for a cabinet, substantially as shown and described.

JEROME E. MOBERG.
